UNITED STATES PATENT OFFICE

LONGINUS A. NEIS, OF DIXON, ILLINOIS, ASSIGNOR TO AMERICAN BODY & CAB COMPANY, OF DIXON, ILLINOIS, A CORPORATION OF ILLINOIS

TRUNK

Application filed August 9, 1932. Serial No. 628,031.

This invention relates to a trunk such as is particularly adapted for mounting at the rear of an automobile. It comprises a mounted fixed section to which is hinged a swinging section adapted, when opened out, to provide with the fixed section an enclosure, open only at the top, with a relatively large capacity.

This invention which is concerned generally with a trunk of the kind mentioned, is directed particularly to certain features of construction by which the swinging section is amply supported when in opened-out position whereby to sustain a heavy load; with means by which the opened-out swinging section is maintained in extended position and prevented from closing up, wholly or partially, in response to any upward vertical forces; and to a simple arrangement and construction of trunk sections the component walls of which co-operate to provide a structure which is strong, durable and rigid, and capable of withstanding hard and continued service. Other objects and advantages will appear more clearly hereinafter from the description and claims, taken in conjunction with the accompanying drawings wherein is exhibited a suggestive embodiment of my invention in the manner following:

Figure 1 is a perspective view of the trunk having its sections in closed relationship, shown as mounted upon a rack or platform at the rear end of an automobile;

Fig. 2 is a view in perspective showing the swinging section of the trunk opened out to provide an enclosure, open only at the top, of large capacity;

Fig. 3 is a fragmentary plan view showing the wall connections adjacent the back of the fixed section;

Fig. 4 is a side elevation of the trunk with the swinging section opened out almost to its limit;

Fig. 5 is a detail in section on line 5 of Fig. 4;

Fig. 6 which is a view similar to Fig. 5, shows the swinging section moved to the fully opened position represented by dotted lines in Fig. 4; and

Fig. 7 is a detail in perspective, partly in

section, exhibiting the supporting hook connection between the hinged and side walls of the trunk.

As illustrated, the trunk comprises a section A adapted for fixed mounting as upon a rack or platform R extended at the rear of an automobile; and a swinging section B which is hinged to the fixed section. The trunk may conveniently be formed of plywood 10 exposed on the trunk interior, backed by plate 11 of some such material as sheet metal and reinforced, if desired, by metallic straps 12 which are extended along the edges of the walls and connected thereto as by rivets 13 which may extend through both the sheet and plywood. Such a construction is advantageous in that it is light and durable and amply strong to meet all requirements of service.

The fixed section comprises a back 15 which upstands from the rear edge of a bottom 16. Extending forwardly from opposite ends of the back are vertical flanges 17. Connected to each flange, as by a piano hinge 18, is a hinged wall 19, the vertical height of which is substantially the same as that of the back. The two hinged walls when folded, as shown in Fig. 3, may be extended past each other so as to occupy a minimum of space within the trunk, and may be releasably secured in this position by a latch 14.

The swinging section comprises a front 20 to which are connected sides 21 and a top 22 all in fixed relationship. Along the bottom of the front, connection is made as by a piano hinge 23 with the forward edge of the bottom, permitting the swinging section to be opened out through 90° or thereabouts. When in closed position, as shown in Fig. 1, the swinging section complements the fixed section to provide a space, enclosed on all sides, which is adapted to receive and protect any articles that are contained therein. As by means of hasp fasteners 24, or other desired fittings, the one section may be locked securely to the other.

In the open position shown in Fig. 2, the two trunk sections provide an enclosure which is open at the top. The sides 21 which extend toward the back only as far as the hinge 23 leave openings which are closable by

the hinged walls 19 when swung out parallel with and adjacent to the sides, as shown. The bottom edges of the hinged walls are desirably cut away at 25 to a slight extent as shown, for a purpose which will presently appear.

To sustain the swinging section in its opened-out position I provide dual supporting means both connected inseparably to the 10 end flanges 17 of the back. One such means consists of a pair of jointed links 26 and 27 pivotally connected at 28, one having a pivotal connection at 29 with its associated flange 17, and the other a pivotal connection 30 with 15 the associated side 21, preferably adjacent its reenforced top edge. One link is provided with a shoulder 31 adapted to overlie the other when the two are brought into alignment, as shown in Fig. 2, thereby limiting unfolding 20 of these links to a straight line position. The links are free to fold only in an upper direction, as indicated by full lines in Fig. 4. When straightened, as shown in Fig. 2, the links will effectively resist any endwise thrust 25 which might be occasioned through a vertical lifting force applied to the swinging trunk section. Accordingly the links, of which a pair may be advantageously used at each end of the trunk, serve both to sustain 30 the swinging section in its fully opened position, and to prevent closing of the swinging section, except when given a breaking motion in an upper direction.

The other means by which the swinging 35 section is sustained in its opened-out position comprises co-acting means on the sides 21 and hinged walls 19 transmitting tension through the latter to the back of the fixed trunk section. As shown, the hinged walls 40 consist each of a metal sheet having its vertical free edge 35 reversely bent to provide a spaced two-ply reenforcement. The ply which faces the associated side 21 is cut out at 36 to form an opening having a bottom edge 37; and co-acting with this edge is a tongue 38 downturned from a plate 39 on the side 21, the tongue forming with the opening a hook connection which is effected by swinging 45 the hinged wall over the tongue just prior to the swinging section reaching its fully 50 opened-out position. With the tongue in a position to hook over the edge 37, the swinging section may be released to drop to its final position where it is sustained by both 55 the hooks and the folding links. To facilitate the swinging movement of the hinged walls necessary for engaging and disengaging with the hooks, I have cut back the lower edge of each hinged wall, as at 25, a distance 60 which permits the swinging section to be raised sufficiently for this purpose. It will be noted that the hook connections just described lie between the confronting faces of 65 the interengaged walls so as to be concealed therebetween.

Other features incorporated into the present trunk include an angle strap 40 extended vertically along the ends of the back, and another angle strap 41 extending beyond the ends of the bottom, the flanges of the straps facing forwardly and upwardly, respectively, so as to enclose the proximate edges of the sides 21 when the swinging section is in closed position. By some such means as this protection to the inside of the trunk is afforded from the exterior.

The construction herein described is of unusual strength, due to the co-operation of the several connecting walls. The horizontal length of the hinged walls is preferably equal to the fore and aft dimension of the bottom plus the vertical height of the front, whereby the free vertical edge of each hinged wall may be positioned adjacent the front wall when the swinging trunk section is extended outwardly, as shown.

The present structure provides an enclosure, open at the top, extending along the sides to a height substantially the same as that of the back, thereby enhancing the capacity of the trunk as well as the safety of the articles which may be carried therein. By the use of piano type hinges, a very strong pivotal connection is made between the two sections of the trunk, and also between the hinged walls and the forwardly facing flanges at opposite ends of the back. The value of such connections is realized through the utilization of the hinged walls as a sustaining means for the swinging section when the latter is opened out to its extended position. Although the folding links, which constitute in effect stay hinges, afford some support to the swinging section, I do not rely wholly upon such means, but rather upon the hinged walls which, when made of heavy steel plate, have ample capacity for sustaining the swinging section together with any load that may be carried in the trunk. The stay hinges serve adequately to resist any upward closing movement of the swinging section, thereby preventing disengagement of the supporting connection with the hinged walls.

I claim :

1. A trunk comprising two complementary hinged sections having, when opened out, overlapping walls with co-acting means concealed between the overlapping walls registering when the trunk sections are opened out nearly to their limit and interengageable when said sections are fully opened, and a folding support inseparably connecting the trunk sections and operable to prevent relative movement thereof with consequent disengagement of the co-acting means.

2. A trunk comprising two complementary hinged sections having, when opened out, overlapping walls with co-acting means concealed between the overlapping walls registering when the trunk sections are opened

out nearly to their limit and interengaging when said sections are fully opened, a fixed mounting for one trunk section whereby the other section is required to move relative thereto during opening and closing movements, and a toggle link support extending from an upper point on the fixed trunk section to a lower point on the other trunk section between the overlapping walls thereof and operable to prevent relative movement of the trunk sections with consequent disengagement of the co-acting means.

3. A trunk comprising mounted fixed and swinging sections, the fixed section having a back and a bottom to the forward edge of which is hinged the bottom edge of a front forming part of the swinging section provided also with sides and a top thereby completing an enclosure when the two sections are in closed relationship, forwardly extended flanges at opposite ends of the back, a wall hinged to each flange having a length substantially equal to the fore and aft dimension of the bottom plus the vertical dimension of the front, the swinging section when opened out to present its front horizontally in line with the bottom providing with the fixed section and hinged walls, when the latter are extended away from the back, an enclosed spaced open only at the top, and coacting means interconnecting the hinged walls with the sides upon relative vertical movement of the swinging section to fully open position to secure the hinged walls in extended position and support the swinging section in its fully open position.

4. A trunk comprising mounted fixed and swinging sections, the fixed section having a back and a bottom to the forward edge of which is hinged the bottom edge of a front forming part of the swinging section provided also with sides and a top thereby completing an enclosure when the two sections are in closed relationship, the swinging section when opened out to present its front horizontally in line with the bottom providing with the fixed section an enclosed space open only at the top and along the sides adjacent the back, and means for supporting the swinging section in opened-out position comprising a pair of walls each hinged vertically adjacent one end of the back and swingable forwardly to positions parallel with and adjacent to the sides of the swinging section, and coacting means on the sides and hinged walls registrable when the swinging section is opened out nearly to the position aforesaid and interengageable upon relative vertical movement of the swinging section to fully open position for hooking the swinging section on to the hinged walls whereby to sustain the former.

5. A trunk comprising mounted fixed and swinging sections, the fixed section having a back and a bottom to the forward edge of

which is hinged the bottom edge of a front forming part of the swinging section provided also with sides and a top thereby completing an enclosure when the two sections are in closed relationship, the swinging section when opened out to present its front horizontally in line with the bottom providing with the fixed section an enclosed space open only at the top and along the sides adjacent the back, and means for supporting the swinging section in opened-out position comprising a pair of walls each hinged vertically adjacent one end of the back and swingable forwardly to positions parallel with and adjacent to the sides of the swinging section, and co-acting means on the sides and hinged walls registrable when the swinging section is opened out nearly to the position aforesaid and interengageable upon relative vertical movement of the swinging section to fully open position for hooking the swinging section on to the hinged walls whereby to sustain the former, the lower edges of the hinged walls being cut away to permit limited vertical swinging movement of the swinging section sufficient for engagement or disengagement of the co-acting means.

6. A trunk comprising mounted fixed and swinging sections, the fixed section having a back and a bottom to the forward edge of which is hinged the bottom edge of a front forming part of the swinging section provided also with sides and a top thereby completing an enclosure when the two sections are in closed relationship, the swinging section when opened out to present its front horizontally in line with the bottom providing with the fixed section an enclosed space open only at the top and along the sides adjacent the back, and means for supporting the swinging section in opened-out position comprising a pair of walls each hinged vertically adjacent one end of the back and swingable forwardly to positions parallel with and adjacent to the sides of the swinging section, and co-acting means on the sides and hinged walls registrable when the swinging section is opened out nearly to the position aforesaid and interengageable upon relative vertical movement of the swinging section to fully open position for hooking the swinging section on to the hinged walls whereby to sustain the former, the lower edges of the hinged walls being cut away to permit limited vertical swinging movement of the swinging section sufficiently for engagement or disengagement of the co-acting means, and toggle means independent of the co-acting means for releasably holding the swinging section in fully opened-out position whereby to normally prevent disengagement of the co-acting means.
